UNITED STATES PATENT OFFICE.

RICHARD CROCKER, OF MAZOMANIE, AND JOHN DIEHL, OF FRANKSVILLE, WISCONSIN.

VEHICLE-SPRING.

SPECIFICATION forming part of Letters Patent No. 371,826, dated October 18, 1887.

Application filed June 23, 1887. Serial No. 242,203. (No model.)

To all whom it may concern:

Be it known that we, RICHARD CROCKER and JOHN DIEHL, of Mazomanie, in the county of Dane, and in the State of Wisconsin, and of 5 Franksville, in the county of Racine, State of Wisconsin, respectively, have invented certain new and useful Improvements in Vehicle-Springs; and we do hereby declare that the following is a full, clear, and exact description 10 thereof.

Our invention relates to vehicle-springs, being an improvement on the device set forth in our application No. 237,671, filed May 10, 1887, and will be fully described hereinafter.

15 In the drawings, Figure 1 is a longitudinal elevation of our invention in place, partly in section. Fig. 2 is a detail, and Fig. 3 is a detail showing a modification.

20 A is a bolster having the usual standards. B is a body-bar, the ends of which are bifurcated, so as to embrace the standards.

On its upper side the bolster is re-enforced, as at *a b a*, by metallic plates to receive the 25 ends of a semi-elliptic spring, C, which ends are slotted to straddle the bolts *c*, the heads *d* of which bind the ends of the springs down on the re-enforces; but as that portion of each bolt just below its head is of greater diameter than the rest of its shank, it forms a shoulder, 30 *e*, that prevents the head from clamping the end of the spring so tightly as to keep it from sliding, and thus interfering with the proper play of the spring.

Just back of the slot, in each end of the 35 spring C, a cup, D, is secured to it, which on its inside receives the lower end of a spring, E, and on its outside is embraced by the lower end of a spring, F, which latter incloses the spring E. The upper ends of the springs F 40 project up through openings in the body-bar B, and each abuts against a plate, G, that is secured to the body-bar by bolts *g g*.

The springs F are longer and stiffer than the springs E, which latter are not designed 45 to come into play unless the load is so great as to depress spring F to the length of spring E.

The center of the spring C is secured to the under side of the center of the body-bar by a 50 plate, H, and bolts *h h*, and this plate carries three springs, K K' K, suspended over the re-enforce *b*. The center spring, K', is longer

than the springs K K, and therefore when bar B is depressed the spring K' begins to act before the springs K K.

As in the modification shown in Fig. 3, we 55 may secure the cups D directly to the re-enforces *a*, and use a shorter spring, C, the ends of which bear each upon one end of a re-enforce, *a*.

To prevent the nuts of bolts *h* from shaking 60 loose and falling off, we may perforate the lower ends of the bolts and insert spring-keys *h'* in these perforations after the nuts have been screwed on.

The plate H is made removable, so that it 65 may be taken off and replaced by a plate carrying only the center spring, K', or the two outside springs, K K; or a plate H may be used without any spring at all, leaving the load to be carried by the springs F, or F and 70 E together, the object of our invention being to provide a spring which may be easily adapted for carrying any load, from the lightest to the heaviest. To center the springs E and F and prevent them from interfering with 75 each other, we provide each set with a washer having a horizontal flange, G', that rests on top of spring F, and between it and plate G, and a barrel, G², that incloses the upper end of spring E and shields it from contact with 80 spring F.

Having thus fully described our invention, what we claim as new, and desire to secure by Letters Patent, is—

1. A vehicle-spring comprising a bar, a 85 semi-elliptic spring, suitable means for securing the ends of the latter to the vehicle-bolster, and two spiral springs of varying length and stiffness arranged one within another and interposed between said ends of the semi-elliptic spring and those of the bar, substantially 90 as set forth.

2. A vehicle-spring comprising a bar, a semi-elliptic spring, suitable means for securing the latter to the vehicle-bolster, spiral 95 springs interposed between the ends of the semi-elliptic spring and those of the bar, and two or more intermediate spiral springs arranged to bear upon the bolster when said semi-elliptic spring is depressed, substantially 100 as set forth.

3. A vehicle-spring comprising a bar, a

- semi-elliptic spring, suitable means for securing the latter to the vehicle-bolster, spiral springs interposed between the ends of the semi-elliptic spring and those of the bar, and 5 three intermediate spiral springs, the center one of which has the greatest length, arranged to bear upon the bolster in proportion to the depression of said semi-elliptic spring, substantially as set forth.
- 10 4. A vehicle-spring comprising a bar, a semi-elliptic spring, suitable means for securing the latter to the vehicle-bolster, cups arranged on the semi-elliptic spring, a spiral spring seated in each cup and arranged to be 15 compressed by a downward movement of the bar, and another spiral spring of greater length and stiffness arranged to surround the one first named, substantially as set forth.
5. A vehicle-spring comprising a bar, a 20 semi-elliptic spring, suitable means for securing the latter to the vehicle-bolster, a washer connected to each end of the bar and provided with a depending barrel, a spiral spring having its upper end inclosed by said barrel and 25 its lower end rested upon the semi-elliptic spring, and another spiral spring of greater length and stiffness arranged to surround the one first named, substantially as set forth.

6. A vehicle-spring comprising a bar, a semi-elliptic spring having slotted ends, bolts 30 having shoulders just below their heads and adapted to secure the semi-elliptic spring to the vehicle-bolster, and spiral springs interposed between the ends of said semi-elliptic spring and those of the bar, substantially as 35 set forth.

7. A vehicle-spring comprising a bar having each end thereof provided with a covered opening, a semi-elliptic spring, suitable means for securing the latter to the vehicle-bolster, 40 and spiral springs interposed between said ends of the semi-elliptic spring and bar and having their upper ends arranged to engage the openings in the latter, substantially as set forth.

In testimony that we claim the foregoing we have hereunto set our hands, at Franksville, in the county of Racine and State of Wisconsin, in the presence of two witnesses.

RICHARD CROCKER.
JOHN DIEHL.
